UNITED STATES PATENT OFFICE

135,153

DESIGN FOR A FLASHLIGHT CASE

Louis W. Gensburg, Chicago, Ill., assignor to
Genco Mfg. Co., Chicago, Ill., a partnership
consisting of Louis W. Gensburg, David Gens-
burg, and Meyer Gensburg

Application February 7, 1942, Serial No. 105,703

Term of patent 7 years

To all whom it may concern:

Be it known that I, Louis W. Gensburg, a citizen
of the United States and a resident of
Chicago, in the county of Cook and State of Illi-
nois, have invented a new, original, and orna-
mental Design for a Flashlight Case, of which
the following is a specification, reference being
had to the accompanying drawing forming a part
thereof, and in which:

Fig. 1 is a perspective view of a flashlight case
showing my new design;

Fig. 2 is a side elevational view of the same on
a substantially slightly larger scale;

Fig. 3 is an end elevational view of the same
also on a substantially larger scale; and

Fig. 4 is a perspective view of the same stand-
ing on end and on a slightly larger scale with
respect to Fig. 1.

The characterizing features of my design for
the flashlight case shown reside in the combina-
tion mirror and cover hinged to the lens bearing
face of the casing and in the specific bail stand
associated with the case as illustrated.

I claim:

The ornamental design for a flashlight case,
as shown and described.

LOUIS W. GENSBURG.
